CLOSURE MEANS

Henry J. Jankowski, North Plainfield, N.J., assignor to Foster Wheeler Corporation, New York, N.Y., a corporation of New York

Application October 5, 1956, Serial No. 614,112

14 Claims. (Cl. 110—1)

This invention relates to vapor generators and more particularly to a closure assembly for sealing access openings in vapor generator walls through which entry may be gained to the interior of the vapor generator.

In large capacity vapor generators of conventional design, access openings or apertures are usually provided in the boiler walls through which access to the interiors of the vapor generators is gained for purposes of inspection and/or repairs. The access openings are closed by closure means, as for example access doors, which are positioned within the openings and bolted to the boiler wall adjacent the perimeter of the openings. The access doors are of unitary construction comprising a metal frame, an exterior metal plate secured to the frame, and an interior body portion adjacent the metal plate consisting of a layer of thermal insulation and a layer of castable refractory material. These access doors are relatively heavy, and require more than one person and/or the use of a hoist to effect removal thereof. For example, superheater access doors which are disposed in the walls of marine vapor generators weigh approximately 180 pounds. In vapor generators wherein an outer casing is provided in closely spaced relationship with the wall of the vapor generator, the removal of an access door is particularly difficult because its removal must be accomplished through an access opening or aperture in the outer casing. Another disadvantage of present access doors is that the metal frame of the door and the metal frame lining the access opening are exposed to hot combustion gases generated in the boiler, which gases cause rapid corrosion of the door frame and the metal frame of the access opening. A further undesirable feature of present access door construction is the leakage of combustion gases into the furnace room through the space between the access door and the frame of the access opening. This leakage causes pollution of the air in the furnace room and is injurious to operating personnel.

Accordingly, it is an object of the present invention to provide a closure assembly for an access opening in a vapor generator wall, which closure assembly is of relatively simple construction and is capable of being readily and easily mounted and removed from an access opening.

Another object of the present invention is to provide a closure assembly which effects a fluid-tight seal with the access opening.

The present invention contemplates a novel access closure assembly for an access opening or aperture in a vapor generator wall, which closure assembly comprises at least one plate member and support means in the walls of the opening or aperture for receiving and supporting said plate member transversely of the opening to thereby divide the latter into two closure sections. A refractory wall is arranged in each closure section adjacent to the inner surface of the vapor generator wall and in abutment with each other and the walls of the opening to thereby seal the access opening. An anchor frame is provided in each closure section adjacent the refractory wall. The anchor frames engage means in each closure section

2

whereby the frames are restrained from movement in a direction toward the refractory wall. Second means are provided for interconnecting the anchor frames of each section with the refractory wall adjacent thereto to prevent movement of the wall in a direction away from the anchor frame. Each section is provided with a cover plate which is disposed against the anchor frames for attachment to the outer surface of the vapor generator wall to retain the anchor frames within their respective closure sections. Each of the anchor frames is constructed to provide spaces between the adjacent cover plate and the adjacent refractory wall and the spaces are filled with heat insulating material.

The invention will be more fully understood from the following detailed description thereof when considered in connection with the accompanying drawings, in which:

Fig. 1 is a fragmentary view, in elevation, of a vapor generator having an access closure assembly in accordance with the present invention, and wherein parts of the assembly are broken away for clarity of illustration;

Fig. 2 is a sectional view taken on line 2—2 of Fig. 1;

Fig. 3 is an enlarged sectional view taken on line 3—3 of Fig. 1;

Fig. 4 is a transverse sectional view taken substantially along line 4—4 of Fig. 1;

Fig. 5 is a sectional view taken on line 5—5 of Fig. 1, somewhat enlarged;

Fig. 6 is an enlarged fragmentary view, in elevation, of an anchor frame and the adjacent refractory wall showing an anchor bolt interconnecting the anchor frame and refractory wall;

Fig. 7 is a perspective view of one of the locking cylinders which secure the anchor bolts to the anchor frames;

Fig. 8 is a fragmentary view, in perspective, of one of the closure sections according to the present invention, showing the cooperative relationship of the frame, the support members, the plate members and the anchor frame;

Fig. 9 is an exploded fragmentary view, in perspective, showing a support member, a plate member, and an anchor frame of the present invention prior to assembly;

Fig. 10 is a perspective view of a cover plate of the present invention; and

Fig. 11 is a fragmentary view, in section, taken along line 11—11 of Fig. 3.

Referring now to the drawings, and more particularly to Fig. 1, 10 designates a side wall of a conventional vapor generator, which vapor generator has an upper vapor-liquid drum 11 (partially shown) disposed in the roof (not shown) of the vapor generator and a liquid drum 12 (partly shown) disposed to the left of the vertical axis of vapor-liquid drum 11 in the floor (not shown) of the vapor generator. The vapor generator is provided with an outer wall or casing 13 (Figs. 1 and 3) which is disposed in spaced, parallel relationship to side wall 10. Side wall 10 is provided with an access opening or aperture 14 which extends between vapor-liquid drum 11 and liquid drum 12 and is inclined to the vertical axis of the vapor generator. An access opening (not shown, since the wall defining the opening is broken away in Fig. 1) is provided in outer casing wall 13 and is disposed to lie in substantial alignment with access opening or aperture 14 in side wall 10. The access opening of outer wall 13 is closed, in a conventional manner, by a plurality of plates 15 (Fig. 2). Access aperture 14 is closed by a closure assembly 16, constituting the present invention which will hereinafter be described in detail.

Closure assembly 16 comprises a metal frame 17 which lines the walls of aperture 14. Frame 17 has spaced, parallel side members 18 and 19 and an upper member or lintel 20 and a lower member or saddle 21. Side members 18 and 19 are L-shaped in cross-section, as best

shown in Figs. 4, 5 and 8, and are each disposed with one leg 22 thereof lying in a recess 23 formed in the aperture side walls 24 and 25 and the other leg 26 lying in a recess 27 formed in the outer surface of wall 10 along the edge of aperture side walls 24 and 25. Legs 22 of side members 18 and 19 extend the length of side walls 24 and 25 and in alignment therewith and inwardly from the exterior surface of wall 10 to a point approximately mid-way between the exterior and interior surface of wall 10 (Fig. 4). Upper and lower walls 28 and 29, respectively, of aperture 14 are recessed, as shown in Fig. 2, to receive lintel 20 and saddle 21, respectively. Side members 18 and 19, are secured as by welding, at their upper ends to lintel 20 and at their lower ends to saddle 21.

A plurality of support members 30 (Figs. 1, 4 and 8) are secured, as by welding or by other suitable means, to the surface of legs 22 of side members 18 and 19 in spaced relationship to each other and lintel 20 and saddle 21. Each support member 30 of side member 18 is arranged opposite a support member 30 of side member 19 to thereby provide pairs of support members spaced from each other along the length of side members 18 and 19. Each pair of support members 30 is constructed and arranged, as hereinafter described, to support a metal plate member 31, hereinafter more fully described. As shown in the drawings, three pairs of support members 30 are provided to receive and support three plate members 31 transversely of aperture 14 to thereby divide the latter into an upper closure section A, two intermediate closure sections B and C, and a lower closure section D. Each support member 30, as best shown in Figs. 8, 9 and 11, comprises a rectangular plate 32 to which is welded, or otherwise suitably secured, an L-shaped spacer member 33. Spacer member 33 has a horizontal leg 34 which extends adjacent the lower edge of plate 32 and a vertical leg 35 which extends adjacent the inner vertical edge of plate 32. Each support member 30 is secured to legs 22 of side members 18 and 19 with spacer member 33 disposed against the surface of legs 22 to thereby position plate 32 in spaced parallel relationship with the surface of legs 22 and to provide a slot 36 defined by plate 32, spacer member 33 and legs 22 of frame 17.

Plate members 31, hereinafter referred to as closure lintels, are rectangular metal plates having a width substantially equal to the width of legs 22 of side members 18 and 19 and having dependent end portions 37. The dependent end portions 37 of each closure lintel 31, are adapted for insertion in slots 36 formed by a pair of support members 30 so that the end portions 37 abut the vertical legs 35 of spacer members 33 (see Figs. 3 and 4) and the under surfaces of closure lintels 31 rest upon the upper edges of plates 32 (best shown in Fig. 11). Each closure lintel 31 is thus supported at each end by a support member 30 transversely within frame 14 and normal to legs 22 of side members 18 and 19. Lintels 31 are restricted against movement in a downward direction by plates 32 of support members 30 and in a direction inwardly from the outer surface of vapor generator wall 10 by abutment of dependent end portions 37 against vertical legs 35 of spacer members 33.

A refractory wall 38, comprising a plurality of refractory bricks 39 arranged in rows, one above the other, is constructed in each of the closure sections A, B, C and D. Refractory walls 38 of intermediate closure sections B and C are constructed to extend upwardly between and in abutment with adjacent closure lintels 31 (Figs. 2 and 3) and between and in abutment with legs 22 of side members 18 and 19 and aperture side walls 24 and 25 (Fig. 4). Refractory wall 38 of closure section A, as shown, is constructed to extend upwardly between legs 22 and aperture side walls 24 and 25 from the uppermost closure lintel 31 to the top wall 28 of aperture 14, while refractory wall 38 of the lower closure section D extends upwardly between legs 22 of side members 18 and 19

and aperture side walls 24 and 25 from bottom wall 29 of aperture 14 to the lowermost closure lintel 31 (Fig. 2). Refractory walls 38 of each closure section A, B, C and D are in contact with each other, adjacent closure lintels 31, to provide a continuous refractory wall structure extending between aperture top and bottom walls 28 and 29, respectively, and side walls 24 and 25. In the construction of refractory walls 38, a very thin coating of mortar is applied between the abutting surfaces of bricks 39 of the walls 38, between the adjacent refractory bricks and the top and bottom walls 28 and 29, and between the bricks and lintels 31 and legs 22 of side members 18 and 19 to thereby prevent leakage of combustion products through aperture 14. The mortar is of a composition, well known to those skilled in the art, which will not fuse into a ceramic bond at high temperatures, as for example approximately 2500° F., so that, when it is necessary to gain access to the interior of the vapor generator, separation of bricks 39 of refractory walls 38 may be accomplished with relative ease and with little or no damage to the bricks.

As shown in Figs. 2 and 3, the lowermost row of refractory bricks 39 of refractory walls 38 of closure sections A, B and C have a portion of their undersurfaces recessed at 40 to receive therein a portion of closure lintels 31 so that the lowermost row of bricks 39 extend over the inner edges of closure lintels 31. With the lowermost row of refractory bricks 39 extending over the entire inner edge of lintels 31 and in abutment with the uppermost row of bricks 39 of the next lower adjacent refractory wall 38, the lintels are shielded from the hot combustion products generated within the vapor generator. Refractory bricks 39 in the lowermost row of refractory walls 38 are also provided with triangular depressions 41 in their recessed surfaces 40. Each closure lintel 31, as best shown in Fig. 8, is provided with a plurality of aligned spaced triangular shaped projections or teeth 42 on the upper surfaces of lintels 31. Teeth 42 project into depressions 41 of lowermost row of refractory bricks 39 to thereby anchor the lowermost row of bricks 39 of refractory walls 38 to closure lintels 31.

Bricks 39 which are placed adjacent support members 30 in closure sections B, C and D are notched at 40A to accommodate therein the adjacent support member 30 and permit the bricks 39 to contact aperture side walls 24 and 25 (see Fig. 4) and thereby shield support members 30 from the combustion products generated within the vapor generator.

A metal anchor frame 43 is disposed in each closure section in contact with the outer surface of refractory walls 38 and is connected to the adjacent refractory wall, as hereinafter described. Each anchor frame 43 of closure section B and C comprises, as best shown in Figs. 3, 8 and 9, an upper angle iron 44 which is connected by three laterally spaced angle irons 45 to a lower angle iron 46. Angle irons 44 and 46 are of a length substantially equal to the distance between side members 18 and 19 of frame 17 so as to fit between said side members. Each of the angle irons 45 is positioned and secured to angle irons 44 and 46 so that, when an anchor frame 43 is placed in a closure section, legs 47 of angle irons 45 lie in contact with and in a plane parallel to the outer surface of the adjacent refractory wall 38. Each leg 47 is provided with a plurality of longitudinally spaced elongated openings 48, the purpose of which will be hereinafter fully explained. The upper angle iron 44 of each anchor frame 43 is so disposed that, when anchor frame 43 is positioned in a closure section, a leg 49 of angle iron 44 lies parallel to the under surface of the adjacent closure lintel 31 and the other leg 50 extends downwardly in a plane normal to the under surface of closure lintel 31. Lower angle iron 46 of each anchor frame 43 is positioned so that the edge of leg 51 thereof abuts against the upper surface of the adjacent lintel 31 and leg 51A is spaced from and ex-

tends parallel to the upper surface of the adjacent lintel 31. The outer surface of legs 50 and 51 of angle irons 44 and 46, respectively, lie in the same vertical plane. Anchor frames 43 of closure sections A and D are similar in construction to anchor frames 43 of closure sections B and C, and differ only in that the upper angle iron 44 of the anchor frame of closure section A is disposed so that legs 49 and 50 thereof lie in abutment against lintel 20, and lower angle iron 46 of anchor frame 43 of closure section D is disposed so that legs 51 and 51A thereof lie in abutment against saddle 21.

Each anchor frame 43 of intermediate closure sections B and C is positioned between adjacent lintels 31 so that leg 50 of upper angle iron 44 contacts, adjacent opposite ends thereof, a pair of lugs 52, one lug being disposed on each of the support members 30 (best shown in Fig. 9). Leg 51 of lower angle iron 46 abuts against two spaced lugs 53 on adjacent closure lintels 31. Lugs 53 are disposed adjacent depending end portions 37 of lintels 31 and inwardly from the outer edge of the lintels so that, when the anchor frames are positioned in closure sections B and C with legs 51 in abutment against lugs 53, the outer surface of legs 51 lie in coplaner relationship with the outer edges of closure lintels 31 and the outer surface of wall 10 of the vapor generator. Lugs 52 of support members 30 are disposed on plates 32 of the support members so that, when anchor frames 43 are positioned in closure sections B and C with leg 50 in abutment against lugs 52, the surface of leg 50 lies in coplanar relationship with the outer edges of lintels 31 and the outer surface of wall 10. Anchor frame 43 of closure section A is positioned so that upper angle iron 44 abuts lintel 20 and the lower angle iron 46 abuts lugs 53 of the uppermost closure lintel 31.

Anchor frame 43 of closure section D is positioned so that upper angle iron 44 abuts lugs 52A which are disposed on the lowermost pair of support members 30 (Figs. 2 and 5). Lugs 52A are similar to lugs 52 of the upper adjacent support members, but are disposed inwardly from the outer vertical edge of plates 32 of support members 30 further than lugs 52 of the upper adjacent support members, so that the anchor frame 43 is positioned against the refractory wall of closure section D which wall, as shown in Fig. 2, is inwardly set back from the plane of refractory walls 38 of closure sections A, B and C.

Anchor frames 43 of closure sections B and C are prevented from moving in a direction toward refractory walls 38 by abutment of the frames against lugs 52 of support members 30 and lugs 53 of closure lintels, as aforescribed. Anchor frame 43 of closure section A is restrained from movement in a direction toward refractory wall 38 by engagement with lintel 20 and lugs 53 of the uppermost closure lintel 31, while anchor frame 43 of closure section D is restrained against movement inwardly toward its associated refractory wall 38 by lugs 52A of the lowermost pair of support members 30 and saddle 21. Sidewise movement of frames 43 is prevented by abutment of the opposite ends of upper angle iron 44 and lower angle iron 46 against legs 22 of side members 18 and 19. The anchor frames 43 of closure sections A, B and C are vertically supported by the next lower closure lintel 31, while lower anchor frame 43 of closure section D is supported by saddle 21.

In the course of constructing each of the refractory walls 38, a plurality of anchor bolts 55 are inserted between every other row of refractory bricks 39 in such manner as to provide laterally spaced rows of bolts 55, the number of bolts corresponding to the number of openings 48 in angle bars 45. Each anchor bolt 55, as best shown in Fig. 3, is L-shaped, having a horizontal leg 56 and an upstanding leg 57. A "diamond"-shaped member 58 is secured at the end of leg 56, normal to the longitudinal axis of leg 56. The adjacent surfaces of bricks 39, between which bricks 39

a bolt 55 is inserted, are provided with matching semi-circular grooves 59 (see Fig. 11) each of which extend from the outer vertical faces of the bricks inwardly to matching triangular depressions 60, depressions 60 being similar to depressions 41 in the lowermost row of bricks 39 adjacent lintels 31. As best shown in Figs. 2 and 3, each bolt 55 is positioned between adjacent bricks 39 so that leg 56 lies in grooves 59 and diamond-shaped member 58 lies in matching depressions 60, and leg 57 extends upwardly in spaced relationship with the outer surface of refractory walls 38. Leg 57 of each anchor bolt 55 projects through an elongated opening 48 of an anchor frame 43 when anchor frames 43 are positioned within the closure sections, as aforescribed.

Each anchor bolt 55 is secured to anchor frames 43 by a locking cylinder 62 (shown in Fig. 7) which has an axial bore 62A of a diameter slightly larger than the diameter of leg 57 of anchor bolt 55 and an outside diameter larger than the width of elongated slots 48. Locking members 62 are passed over the end of upstanding legs 57 of anchor bolts 55 and secure the latter to anchor frames 43 by preventing legs 57 of the anchor bolts 55 from passing through openings 48. Angle iron legs 50 of anchor frame 43 of intermediate closure sections B and C are provided with notches 54 (see Figs. 6 and 8) to facilitate slipping locking members 62 on legs 57 of the uppermost anchor bolts 55. Any movement of refractory walls 38 in a direction inwardly away from anchor frames 43 is prevented by the latter through bolts 55, anchor frames 43 being prevented from moving inwardly by lugs 52, 52A, and 53 and lintel 20 and saddle 21, as aforescribed.

A layer of high temperature insulating material 63 is disposed within anchor frame 43 of closure section A, B, C and D. Each layer of insulating material 63 comprises a plurality of blocks 64. Blocks 64 are arranged in the spaces defined by endmost angle irons 45 and the adjacent side members 18 and 19 of frame 17 and upper and lower angle irons 44 and 46. Blocks 64 are also arranged in the spaces defined by angle irons 45 and upper and lower angle irons 44 and 46. Blocks 64 are suitably recessed at 65 (Fig. 3) to accommodate therein anchor bolts 55 and locking cylinders 62, and is suitably cut-out (not shown) to accommodate therein support members 30 so that the layer of insulating material lies flat and flush with or extends slightly outwardly of the outer surface of refractory wall 10. The layer of insulating material 63 is partially shown only in Fig. 3 and has been entirely omitted from Figs. 1, 2, 4 and 5 for the sake of clarity.

The assembly of intermediate closure sections B and C is completed by cover plates 66 which are disposed to overlie anchor frames 43 in abutment against the surface of legs 50 and 51 of upper angle bars 44 and 46, respectively (see Figs. 2 and 3). Each of the cover plates 66, as shown in Fig. 10, comprises a relatively thin metal plate which is dimensioned to extend between adjacent closure lintels 31 and to slightly overlap the edge of aperture walls 24 and 25. Cover plates 66 are provided with outwardly extending upper flanged edges 67 and lower flanged edges 68, and are reinforced by spaced parallel ribs 69 which are secured, as by welding, to the outer surface of said cover plates 66. Cover plates 66 are provided with reinforcing strips 66A which are secured, as by welding, to flanges 67 and 68 and along the lateral edge portions thereof to lend rigidity to the cover plates 66.

Upper closure section A is provided with a cover plate 70 which is similar in construction to cover plates 66 and differs from the latter in that only the lower edge of the plate is flanged, as shown at 71, the upper portion 72 of cover plate 70 extending slightly beyond lintel 20 and flush with wall 10. Cover plate 70 is provided with reinforcing strips 70A, similar to strips 66A of cover plates 66, which strips 70A are secured, as by welding,

to flange 71, the lateral edges of the cover plate, and to upper portion 72 thereof.

Lower closure section D is provided with a cover assembly 73 which comprises spaced parallel inner and outer plates 74 and 75, respectively, which are secured together along their edges. A layer of high temperature insulating material 76 is disposed in the space between plates 74 and 75. The upper edge of cover member 73 is provided with an outwardly extending flange 77 while the lower edge is flanged at 78 so as to overlap saddle 21 and lie flush against wall 10 of the vapor generator. Two spaced parallel ribs 79, similar to ribs 69, are secured to the outer surface of plate 75.

Cover plates 66, cover plate 70 and cover assembly 73 are disposed so that flange 71 of cover plate 70 contacts upper flange 67 of cover plate 66 of the intermediate closure section B, while lower flange 68 of cover plate 66 of closure section B contacts upper flange 67 of cover plate 66 of closure section C, and lower flange 68 of cover plate 66 of closure section C engages flange 77 of cover member 73 of closure section D. The abutting flanges 67, 68, 71 and 77, including reinforcing strips 66A and 70A which are secured to the flanges, are each provided with a plurality of spaced bores 80 which are brought into register to receive bolts 81 for securing together cover plates 66 of closure sections B and C, cover plate 70 of closure section A to cover plate 66 of closure section B and cover assembly 73 of closure section D to the cover plate 66 of closure section C. The lateral edge portions of cover plates 66, cover plate 70 and cover assembly 73 are secured to wall 10 by a plurality of spaced fastening members 82. Each of the fastening members 82, comprise as shown in Figs. 4 and 5, a U-shaped bar 83 which is disposed so that one leg bears against the lateral edge portions of the cover plates 66 and 70 and cover assembly 73 and the other leg bears against wall 10, adjacent aperture 14. Each U-shaped bar 83 is drawn tight against cover plates 66 and 70 and cover assembly 73 and wall 10 by a bolt 84 which extends through a hole in bar 83 and is threaded into bores in wall 10. The upper edge portion 72 of cover plate 70 and flange 78 of cover member 73 are also secured to wall 10 by a plurality of spaced fastening members 82.

In order to gain access to the interior of the vapor generator through aperture 14, one or more of the closure sections A, B, C or D is removed. Let it be assumed that access is desired through closure section B (best shown in Fig. 3) of closure assembly 16. Cover plate 15, opposite closure section B, is unfastened from casing wall 13 and the adjacent upper and lower cover plates 15 and removed to permit access to closure section B. Removal of cover plate 66 of closure section B is accomplished by loosening bolts 84 of the fastening members 82 so that U-shaped bars 83 may be rotated about bolts 84 to free the lateral edge portions of cover plate 66. Bolts 81, which secure lower flange 68 of cover plate 66 to upper flange 67 of the adjacent cover plate 66 of closure section C, are then removed from bores 80. Bolts 81, which secure upper flange 67 of cover plate 66 to lower flange 71 of cover plate 70 of closure section A, are removed from bores 80. With the lateral portions of cover plate 66 unfastened from wall 10, and flanges 67 and 68 of cover plates 66 unbolted from the flanges of the adjacent upper and lower cover plates, cover plate 66 can be removed. After removal of cover plate 66, blocks 64 of heat insulating material are removed to expose anchor bolts 55. Anchor frame 43 then is disconnected from its associated refractory wall 38 by sliding each of the locking cylinders 62 from legs 57 of anchor bolts 55. With the removal of locking cylinders 62, legs 57 of anchor bolts 55 are free to pass through elongated openings 48 as the anchor frame is withdrawn from between lintels 31 and side members 18 and 19. After anchor frame 43 is removed, refractory wall 38 is then removed by separating bricks 39 of the wall and removing the anchor bolts 55

as they are exposed. Since bricks 39 are not ceramicly bonded together or to legs 22 of side members 18 and 19 and lintels 31, separation of the bricks 39 is accomplished with relative ease and with little or no damage to the bricks. Disassembly of wall 38, for example, may be started by working a thin tool around bricks 39, designated X and Y in Fig. 3, in between the abutting surfaces of bricks 39 and bricks X and Y to break the non-ceramic bond therebetween. After bricks X and Y are freed from the surrounding bricks, bricks X and Y can be removed from wall 38 by using anchor bolt 55, which lies between bricks X and Y, as a handle. Thereafter, the remaining bricks 39 may be readily separated and removed. As can be seen, removal of closure section B is accomplished without disturbing or affecting the adjacent closure sections A, C and D, the adjacent closure sections A and C being vertically supported by closure lintels 31 and closure section D being supported by saddle 21.

To re-assemble closure section B, refractory wall 38 is reconstructed with anchor bolts 55 inserted between adjacent bricks in the manner aforescribed using the same bricks 39, or some new bricks 39 to replace damaged or defective bricks, if necessary, or may be constructed entirely of new refractory bricks. Anchor frame 43 is then positioned with its upper angle iron 44 in contact against lugs 54 of support members 30, with its lower angle iron 46 in abutment against lugs 53 of the lower closure lintel 31, with legs 47 of its angle irons 45 in abutment against the outer surfaces of refractory wall 38, and with legs 57 of anchor bolts 55 extending through elongated openings 48 in legs 47 of anchor frame 43. Thereafter, locking cylinders 62 are slipped on legs 57 of bolts 55 to secure the refractory wall to anchor frame 43. Heat insulating blocks 64 are then placed within anchor frame 43, as aforescribed. Cover plate 66 is then repositioned against anchor frame 43 so that bores 80 in upper flange 67 are in register with bores 80 in flange 71 of the upper adjacent cover plate 70, and bores 80 in lower flange 68 are in register with bores 80 in upper flange 67 of the next lower cover plate 66. Bolts are then inserted in bores 80 and nuts threaded thereon to secure together adjacent flanges 67 and 71 and adjacent flanges 67 and 68. The U-shaped bars 83 of fastening members 82 are repositioned so as to engage the lateral edge portions of cover plate 66 and bolts 82 are tightened to secure cover plate 66 to refractory wall 10.

The other closure sections A, C and D are removed by the same procedure as disclosed with respect to closure section B. If two or more adjacent closure sections are removed, closure lintel 31 disposed between the sections may also be removed by sliding dependent end portions 37 out of engagement with slots 36 formed between support members 30 and surface of legs 22 of side members 18 and 19. Removal of one or more closure lintels 31 between two or more closure sections provides a large unobstructed opening to the interior of the vapor generator.

The present invention, as now can be understood, provides a closure assembly for an access aperture which assembly comprises two or more closure sections. Each closure section is removable from the access aperture by disassembly of the component parts thereof, which disassembly may be accomplished by one individual and without the use of hoists or the like. The closure assembly of the present invention also eliminates combustion gas leakage and the resultant corrosion of metal parts which occurs in conventional unitary access door structures.

Although but one embodiment of the present invention has been illustrated and described in detail, it is to be expressly understood that the invention is not limited thereto. Various changes can be made in the arrangement of parts without departing from the spirit and

scope of the invention, as the same will now be understood by those skilled in the art.

What is claimed is:

1. A closure arrangement for an access aperture in a wall of a heating apparatus, comprising at least one plate member, at least two support members secured to said wall within said access aperture and opposite each other for receiving the opposite ends of the plate member to support the latter within said access aperture to thereby divide said aperture into at least two closure sections, a refractory wall constructed and arranged within each closure section adjacent the inner surface of the heating apparatus wall and set back from the outer surface of said wall to provide a recess in each closure section, said refractory walls being in abutment with the aperture walls and said plate member and each other to seal the access aperture, an anchor frame disposed in the recess of each section adjacent the refractory wall thereof, said plate member and said support members having means for engaging the anchor frames to restrain movement of the anchor frames in the direction toward the refractory walls and allowing movement of the anchor frame in a direction away from the associated refractory wall, detachable means connecting the refractory wall and the anchor frame of each closure section to prevent movement of the refractory walls in a direction away from the anchor frame, and a cover plate for each closure section detachably connected to the outer surface of the heating apparatus wall to retain the anchor frames within the closure sections.

2. The structure of claim 1 wherein each of the anchor frames is constructed and dimensioned to provide at least one space between the adjacent refractory wall and the cover plate of each section for receiving heat insulating material.

3. The structure of claim 1 wherein each of the refractory walls comprises a plurality of refractory bricks disposed adjacent each other in a fluid-tight manner and in fluid-tight abutment with the adjacent refractory walls and the walls of the vapor generator.

4. A closure means for an access aperture in a wall of a heating apparatus which access aperture has top and bottom walls and substantially vertical side walls, the closure means comprising at least one plate member, at least two support members secured opposite each other to said side walls of the aperture for receiving the opposite ends of the plate member to support the latter horizontally within and across said aperture and in spaced relationship to the top and bottom aperture walls to thereby divide the access aperture into two closure sections, a refractory wall disposed in each closure section and set back from the plane of the exterior surface of the wall of said heating apparatus to provide a recess in each closure section, the refractory walls of each section being disposed in abutment with the plate member and the aperture walls to seal the access aperture, an anchor frame disposed in the recess of each closure section, said plate member and the support members having means for engaging said anchor frame members to restrain movement thereof in a direction toward the refractory walls and allowing movement of the anchor frame in a direction away from the associated refractory wall, detachable means connecting each of said anchor frame members and the adjacent refractory wall to support the latter against movement away from said anchor frame members, and a cover plate for each closure section disposed adjacent said anchor frame members and detachably connected to the heating apparatus wall to retain the plate member and anchor frame members in each section.

5. The closure means of claim 4 wherein the plate member and the above adjacent refractory wall are provided with means for interlocking one with the other.

6. A closure means for an access aperture in a vapor generator wall, comprising a plurality of plate mem-

bers, a pair of support members for each plate member, the support members of each pair of support members being secured opposite each other to opposite walls of said aperture and in spaced relationship with the next adjacent pair of support members, each pair of support members receiving a plate member to support the same within said aperture to thereby divide the access aperture into a plurality of closure sections, a refractory wall disposed within said access aperture in each closure section and set back from the plane of the exterior surface of said vapor generator wall to provide a recess in each closure section, the refractory walls of each section being disposed in abutment with the plate members and the aperture walls to seal the access aperture, an anchor frame member disposed in the recess of each closure section adjacent said refractory wall thereof, said support members and said plate members having means for engaging said anchor frames to restrain the latter from movement toward the refractory wall and allowing movement of each anchor frame in a direction away from its associated refractory wall, detachable means for connecting each of said anchor frame members and the associated refractory wall to restrain movement of the latter in a direction away from the anchor frames, and a cover plate in each section disposed adjacent said anchor frame members and detachably connected to the vapor generator wall to retain the anchor frames in said closure sections.

7. A closure means for an access aperture in a vapor generator wall, comprising a plurality of plate members, a pair of support members for each plate member, the support members of each pair of support members being secured opposite each other to opposite walls of said aperture and in spaced relationship with the next adjacent pair of support members, each pair of support members receiving the opposite ends of a plate member to support the same and thereby divide the access aperture into a plurality of closure sections, a refractory wall disposed in each closure section and set back from the plane of the exterior surface of the vapor generator wall to provide a recess in each closure section, the refractory walls being constructed and arranged to abut the plate members and to join each other and the aperture walls in fluid-tight relationship to thereby seal said access aperture, an anchor frame member disposed in the recess of each closure section adjacent the refractory wall thereof, said support members and plate members having means for engaging the anchor frames to restrain the anchor frames against movement toward the adjacent refractory walls and allowing movement of the anchor frames in a direction away from the adjacent refractory walls, detachable means for connecting each anchor frame member and the adjacent refractory wall to secure the wall against movement in a direction away from the anchor frame member, a cover plate disposed adjacent each of the anchor frame members and detachably connected to the vapor generator wall to retain the plate and anchor frame members in each closure section of the access aperture.

8. A closure means for an access opening in a vapor generator wall, comprising a plurality of plate members, a pair of support members for each plate member, the support members of each pair of support members being secured opposite each other to opposite walls of the access opening and in spaced relationship with the next adjacent pair of support members, each pair of support members receiving the opposite ends of a plate member to support the same between opposite walls of the access opening to thereby divide the access opening into a plurality of closure sections, a plurality of refractory bricks arranged in fluid-tight relationship to each other to form the refractory wall in each section set back from the plane of the exterior surface of the vapor generator wall to provide a recess in each closure section, the refractory wall of each section being ar-

11

ranged to abut the adjacent plate members and to join each other and the vapor generator wall in a fluid-tight relationship and to thereby seal said access opening, an anchor frame member disposed in the recess of each closure section adjacent the refractory wall thereof, each anchor frame member comprising two spaced first angle irons and a plurality of spaced second angle irons extending between and connected to said first angle irons thereby forming a plurality of spaces between said first and second angle irons, said plate members and support members having stop lugs for engaging the anchor frames to restrain the latter from movement toward refractory walls and allowing movement thereof in a direction away from the refractory walls, a plurality of anchor bolts disposed in each closure section in engagement with the refractory bricks of the refractory wall and the second angle irons of the anchor frame in each closure section to secure the refractory walls against movement in a direction away from the adjacent anchor frame members, a cover plate disposed in abutment against each of the anchor frame members and detachably connected to the vapor generator wall to retain the plates and the anchor frame members in each closure section of the access opening, and heat insulating blocks disposed in the spaces between the first and second angle irons of the anchor frame members and the refractory walls and the cover plates.

9. A closure means for an access aperture in a vapor generator wall which access aperture extends from the exterior surface to the interior surface of the vapor generator wall to provide end surfaces defining said access aperture, comprising a frame having side members and a top and bottom member, said frame lining the end surfaces of the vapor generator wall defining the access aperture and extending along the end surfaces from the exterior surface of the vapor generator wall to a point short of the interior surface of the vapor generator wall, at least one plate member, at least two support members disposed and secured one on each side of said side members of the frame for receiving the opposite end portions of said plate member for supporting the latter in spaced relationship to the top and bottom members of the frame to thereby divide the access aperture into at least two closure sections, a refractory wall constructed of a plurality of refractory bricks joined together in fluid-tight relationship and set back in each closure section from the plane of the exterior surface of the vapor generator wall to provide a recess in each closure section, the refractory walls being arranged adjacent the inner surface of the aperture walls to partly abut the plate member and the side members of the frame and to join each other and the aperture walls in a fluid-tight relationship to thereby seal said access aperture, an anchor frame member insertable in the recess of each closure section adjacent the refractory wall thereof, each of the anchor frame members comprises two spaced first angle irons and a plurality of spaced substantially parallel second angle irons extending between and connected to said first angle irons thereby providing a plurality of spaces between said first and second angle irons, each of said support members and said plate member having means for engaging the first angle irons of said anchor frames for restraining the anchor frames against movement in a direction toward the interior surface of the vapor generator wall and allowing movement of the anchor frame in a direction away from the adjacent refractory wall, means interconnecting each anchor frame and the adjacent refractory wall to secure the wall against movement in a direction away from the anchor frame member, a cover plate disposed in abutment against each of the anchor frames and detachably connected to the exterior of the vapor generator wall to retain the anchor frames in each closure section, and a heat insulating wall consisting of a plurality of insulating blocks disposed in the spaces between the first

12

and second angle irons of the anchor frame members and the refractory walls and the cover plates.

10. The structure of claim 9 wherein the plate member is provided with means for interlocking with the lower portion of the upper adjacent refractory wall.

11. The structure of claim 9 wherein the support means includes means for restraining movement of the plate member in a direction toward the interior surface of the vapor generator.

10. 12. A multi-sectional closure means for an access aperture which extends substantially vertically and from the exterior surface to the interior surface of a vapor generator wall to provide end surfaces defining the access aperture, comprising a frame having side members and a top

15 and bottom member, said frame lining the end surfaces of the vapor generator wall defining the aperture and extending along the end surfaces from the exterior surface of the vapor generator wall to a point short of the interior surface of the vapor generator wall, a plurality of plate members disposed to extend between the side members

20 of the frame, a plurality of support members secured to each of the side members in spaced relationship to each other and to the top and bottom members of the frame, the support member on each side member engaging an opposite end portion of each plate member so that said

25 plate members divide the access aperture into a plurality of closure sections, a refractory wall disposed in each section and set back from the plane of the exterior surface of the vapor generator wall to provide a recess in each

30 closure section, each of said refractory walls consisting of a plurality of refractory bricks joined together in fluid-tight relationship to each other, the refractory walls being constructed and arranged in each closure section adjacent the interior surface of the vapor generator wall to abut

35 in a fluid-tight manner the plate members and the side members and top and bottom members of the frame and to join each other adjacent the plate members and the aperture walls adjacent the side members, top and bottom members of the frame to thereby seal the access aperture,

40 an anchor frame insertable in the recess of each closure section adjacent the refractory wall thereof, each of said anchor frames comprising two spaced first angle irons, a plurality of spaced second angle irons extending between and connected to said first angle irons thereby forming a

45 plurality of spaces between said first and second angle irons, said plate members and the support members having means for restraining movement of the anchor frames in a direction toward the interior surface of the vapor generator wall, a plurality of anchor bolts disposed in each

50 section for engaging at one end the bricks of the refractory walls and at the opposite end the second angle irons of the anchor frames for anchoring the refractory walls against movement away from the anchor frames, a removable cover plate for each section disposed against

55 the plate members and the anchor frames and detachably connected to the exterior surface of the vapor generator wall to retain the plate members and the anchor frames in each section, and a heat insulating wall consisting of a plurality of insulating blocks disposed in said spaces

60 between the first and second angle irons of the anchor frame and the refractory walls and the cover plates.

13. The structure of claim 12 wherein each support member comprises a plate spaced from the surface of the side member of the frame to define a slot between the

65 plate and the surface of the frame, and wherein the plate members are provided with opposite pendent end portions receivable in the slots of the support members.

14. A multi-sectional closure means for an access aperture which extends substantially vertically and from the exterior surface to the interior surface of a vapor generator wall to provide end surfaces defining the access aperture, comprising a frame lining the end surfaces of the vapor generator wall defining the access aperture and extending along the end surfaces from the exterior surface of the vapor generator wall to a point short of the

13

interior surface of the vapor generator wall, said frame consisting of side members connected at their top portions to a lintel and at their bottom portions to a saddle, a plurality of support members secured to each of the side frame members in spaced relationship to each other and spaced from the lintel and the saddle, the support members of one side member being disposed opposite the support members of the opposite side member of the frame to thereby provide pairs of support members, a plurality of plate members corresponding in number to the number of pairs of support members, each of said plate members dimensioned to extend between a pair of support members and having opposite end portions adapted to engage a support member of each pair of support members, said plate members dividing the access opening into at least one intermediate closure section and adjacent top and bottom closure sections, a refractory wall disposed in each closure section and set back from the plane of the exterior surface of the vapor generator wall to provide a recess in each closure section, each of said refractory walls being constructed of a plurality of refractory bricks joined together in fluid-tight relationship for sealing the access opening, the refractory wall of each section being constructed and arranged within the access aperture to partly abut along its sides the side members of the frame and the end surfaces of the vapor generator wall defining the access aperture adjacent the side members, and to partly abut the plate members and each other adjacent said plate members, the refractory wall of the top and bottom closure sections being disposed so as to partly abut along their bottom surface the lintel and the saddle of the respective closure sections and the end surfaces of the vapor generator wall adjacent the lintel and the saddle of the respective closure sections, an anchor frame insertable in the recess of each closure section adjacent the refractory wall thereof, each of said anchor frames comprising two spaced first angle irons, a plurality of spaced substantially parallel second angle irons extending between and connected to said first angle irons thereby forming a plurality of spaces between said first and second angle irons, each of said support members having a stop member, each of said

35

40

14

plate members having a pair of stop members, first angle irons of the anchor frame of the intermediate section being in engagement with said stop members of a pair of support members and the stop members of the lower 5 adjacent plate member whereby the anchor frame is positioned in the section and prevented from movement in a direction toward the interior surface of the vapor generator wall and allowed to move in a direction away from the interior surface of the vapor generator wall, the first angle irons of the anchor frame of the top and bottom closure sections being in engagement with the stop members of the plate members of their respective closure sections and the lintel and saddle of the respective closure sections for positioning the anchor frames in the respective closure sections and preventing movement of the anchor frames in a direction toward the interior surface of the vapor generator wall and allowing movement of the anchor frames in a direction away from the interior surface of the vapor generator wall, a plurality of anchor 10 bolts disposed in each section for engaging at one end the bricks of the refractory walls and at the opposite end the second angle irons of the anchor frames to anchor the refractory walls against movement away from the anchor frames, a removable cover plate for each 15 closure section disposed against the first and second angle irons of the anchor frames and detachably connected to the exterior surface of the vapor generator wall and to the adjacent cover plate to retain the anchor frames in each section, and a heat insulating wall consisting of the anchor frames and the refractory walls and the adjacent cover plates.
